ECONOMY FILE

Edwin L. Kurth, Mitchell, S. Dak.

Application March 2, 1939, Serial No. 259,456

4 Claims. (Cl. 129—21)

This invention relates to file boxes and more particularly to a file box constructed of cardboard or similar material.

The object of the invention is to provide a file box of simple and inexpensive construction for filing letters, bills, papers and other documents, said file box being made of cardboard so as to economize in cost of structural material and consequently reduce the cost of manufacture.

10 A further object of the invention is to provide a file box having its opposite sides open and its top and front and rear walls closed to form a receptacle adapted to receive the letters or other documents to be filed, the bottom of the box or receptacle being provided with letter impaling pins and the rear wall thereof hinged to said bottom so as to permit convenient access to the contents of the file box when desired.

20 A further object of the invention is to provide a file box which is light in weight, durable in construction and efficient in operation.

Further objects and advantages will appear in the following specification.

In the accompanying drawing forming a part 25 of this specification and in which similar numerals of reference indicate corresponding parts in all the figures of the drawing:

30 Figure 1 is a perspective view of a cardboard filing box constructed in accordance with the present invention, the back wall of the box being shown in dotted lines in open position,

Figure 2 is a transverse sectional view taken on the line 2—2 of Figure 1,

35 Figure 3 is an enlarged vertical sectional view taken on the line 3—3 of Figure 2, and

Figure 4 is a transverse sectional view taken on the line 4—4 of Figure 2.

The improved filing box forming the subject-matter of the present invention is preferably 40 formed of corrugated cardboard to reduce the weight thereof and the cost of manufacture, said box comprising a substantially rectangular receptacle 5 having its opposite sides open and its top 6, bottom 7 and rear wall 8 firmly united to form a rigid structure defining an interior compartment for the reception of the letters, bills and other documents to be filed. The top 6 and rear wall 8 of the receptacle are preferably formed of two plies of cardboard fastened together by cement or other suitable adhesive material, while the bottom 7 is constructed from three plies of cardboard, as best shown in Figures 2 and 3 of the drawing. The uppermost cardboard ply 9 of the bottom of the receptacle is cut-away adjacent the rear wall 8 thereof to form a seating recess

10 for the reception of a cross bar 11 preferably formed of wood. This cross bar 11 is secured within its seat by screws or similar fastening devices 12 extending through reinforcing plates 13 interposed between the intermediate and lowermost ply of the bottom, as best shown in Figure 3 of the drawing. The bar 11 is thus firmly anchored to the bottom of the receptacle so as to prevent accidental displacement thereof. Formed in the lower surface of the bar 11 is a 10 groove 14 having spaced openings 15 communicating therewith and which openings receive the upstanding pins 16 of a U-shaped impaling member. The piercing points 17 of the impaling pins are spaced from the inner surface of the top wall 18 of the box while the connecting yoke 19 of the impaling member is seated within the groove 14 and rests against the intermediate ply of cardboard constituting the bottom of the file box. The impaling pins 16 are also spaced from the 20 rear wall 8 of the receptacle so as to permit letters, bills and other papers or documents to be readily impaled on said pins for future reference. The back wall 19 of the file box is preferably 25 formed from a single ply or sheet of corrugated cardboard, and said back wall is hinged to the bottom wall by a strip of fabric, canvas or other suitable material 20 so as to permit said back wall to be conveniently swung downwardly when it is desired to obtain access to the contents of the 30 box. Securing tapes 21 are fastened to the top of the receptacle and back wall 19 near their free ends by suitable staples 22 so that, when the file box is not in use, the rear wall thereof may be 35 securely held in closed position by tying the tapes into a bow knot, as best shown in Figure 1 of the drawing. The upper cardboard ply 9 of the bottom 7 preferably terminates in spaced relation to the inner face of the back wall 19 to form a shallow recess 23 defining a transverse shoulder 24, and this recess and shoulder permit the operator to readily grasp the adjacent ends of the papers and thus facilitate indexing and sorting said papers before they are impaled on the pins 16. Inasmuch as the file boxes are flat and light in weight, they may be stacked one upon the other on a shelf or in a suitable cabinet. In order to facilitate the removal of a selected file box, the front wall 8 thereof is provided with a handle 25 preferably formed of a single strip of tape, the opposite ends of which pass through incisions 26 in the outer ply of cardboard and are cemented or otherwise secured between the inner and outer plies of cardboard constituting 50 55

the front wall 8 of the box, as best shown in Figure 4 of the drawing.

- 5 By making the file box of corrugated cardboard not only is the weight of the box reduced to a minimum but said file box is sufficiently rigid and strong to effectually withstand rough usage to which it may be subjected in the handling thereof, thereby materially economizing in both weight and cost of manufacture.
- 10 It will, of course, be understood that the file boxes may be made in different sizes and shapes and finished in any color or stain and, if desired, the walls of the boxes may be covered with shellac or wax to resist warping and render 15 the file boxes thoroughly water-proof.

Having thus described the invention, what is claimed as new is:

- 20 1. A file box comprising an open-sided receptacle having united top, bottom and front walls formed of superposed plies of cardboard, the uppermost ply of cardboard constituting the bottom wall of the receptacle being cut-away to form a seating recess, a bar seated in said recess, an impaling member anchored on the bar, a back wall pivoted to the bottom of the receptacle, and interengaging fastening devices carried by the top of the receptacle and said back wall.
- 25 2. A file box comprising an open-sided receptacle having united top, bottom and front walls, the upper surface of the bottom wall being cut-away at one end thereof to form a transverse recess defining a vertical shoulder and the upper surface of the bottom wall at the other end thereof being provided with a seating recess, a transverse bar fitted in said seating recess and having its lower surface formed with a groove opening through the upper surface of the bar, a U-shaped impaling member having its closed 30 end fitted in the groove in the bar and its opposite ends extending through the openings in the bar and terminating in impaling points, a back wall hinged to the bottom wall adjacent the transverse recess, and interengaging fasten-

ing devices carried by the top of the receptacle and said back wall.

3. A file box comprising an open-sided receptacle having rigidly united top, bottom and front walls formed of superposed plies of cardboard, the upper ply of cardboard constituting the bottom wall being cut-away to form a seating recess, a transverse bar fitted in said recess and having a groove on its under surface opening through the top of the bar, anchoring plates interposed between the bottom and intermediate cardboard plies of the bottom wall, fastening devices extending through said anchoring plates and engaging the bar, a substantially U-shaped impaling member having its closed portion seated in the groove in the bar and its opposite ends extended through the openings in said bar and terminating in piercing points, a back wall pivotally connected with the bottom wall, and interengaging fastening devices carried by the top of the receptacle and said back wall for normally holding the back wall in closed position.

4. A file box comprising an open-sided receptacle having united top, bottom and front walls formed of superposed plies of corrugated cardboard, a finger-engaging loop mounted on the outer surface of the front wall and having its opposite ends interposed between the cardboard plies of said front wall and united thereto, the upper cardboard ply of the bottom wall of the receptacle being cut-away adjacent the front wall of the receptacle to form a seating recess, a transverse bar fitted in said seating recess, anchoring plates interposed between certain of the cardboard plies of the bottom wall, fastening devices carried by said anchoring plates and engaging said bar, an impaling device projecting vertically from the bar in spaced relation to the front wall of the receptacle, a back wall pivotally connected with the rear end of the bottom wall, and interengaging fastening devices carried by the top of the receptacle and the back wall for holding said back wall in closed position.

EDWIN L. KURTH.
